UNITED STATES PATENT OFFICE.

IRA D. SHARP, OF NICHOLASVILLE, KENTUCKY.

APPARATUS FOR PRINTING PHOTOGRAPHS FROM NEGATIVES.

Application filed May 23, 1923. Serial No. 640,955.

This invention relates to an apparatus for the printing of photographs from negatives and more particularly to that type of printing machine described and claimed in my

5 Patent No. 1,521,399, dated December 30, 1924.

An object of the invention is the provision of a device for printing photographs in which the intensity of the light may be varied according to the density of the negatives and in which the time of exposure remains constant for photographic papers of constant speed.

A further object of the invention is the provision of a device for printing photographs having an automatically controlled time element for operating a switch of an electric circuit to close and open the circuit whereby the proper exposure may be had and the time of exposure be limited to a definite period of time or the time element may be so controlled for varying the period of exposure according to the sensitiveness of the paper.

25 Another object of the invention is the provision of a compact and unitary structure for printing photographs in which the intensity of the light may be accurately varied according to the density of the negatives and the speed of the paper and in which the operation of the light and time of exposure is controlled by the operation of an element connected with the usual platen.

A still further object of the invention is the provision of a unitary and compact device for printing photographs in which the operation of the platen causes the actuation of a time element for determining the period of exposure of the printing paper, the time element automatically operating a switch for closing a circuit and the switch and time element being so constructed that either one may be removed without disturbing the other element.

45 Other objects and advantages will become apparent during the course of the following description.

The invention is illustrated by way of example in the accompanying drawings, in which:

50 Figure 1 is a view in perspective of the apparatus for the printing of photographic prints from negatives.

Figure 2 is a vertical longitudinal section of the printing apparatus.

55 Figure 3 is a diagrammatic representation of the wiring.

Referring to the drawings, 1 designates a table having an inclined portion 2 and supported by pairs of legs 3. The main body of the table is adapted to be located horizontally. The inclined portion 2 of the table is provided with an opening 4 which is covered by a transparent member 5 upon which is adapted to be placed the negative 6 to be printed. Secured to the bottom portion of the member 2 of the table and embracing the opening 4 is a casing 7 forming a housing for the lamp 7 and a reflector for the light to be projected through the negative located on the transparent member 5. Any form of reflectors may be employed within the casing 7. While I have shown one lamp 7 any number of lamps may be employed as may be desired. A red lamp 8 is disclosed in circuit with the house current for illuminating the interior for working purposes of the apparatus.

70 A horizontal block 9 is secured to the table top and upon which is hingedly mounted a platen 10 at 11. Secured to the outer end of the platen 10 is a block 12 provided on its outer face with any form of felt or other material in order to firmly and evenly press the paper and negative into close contact with each other and with the glass printing surface. Hingedly mounted upon the outer end of the platen 10 at 13 is a second block 14 likewise provided with felt 20 or other suitable material similar to the material disposed upon the outer face of the block 12.

75 An operating lever 21 is hingedly mounted upon the hinge pin 11 and is adapted to be operated within a slot 22 formed in the platen 10. Springs 23 and 24 connect the lever 21 respectively to the platen 10 and the block 14 so that when the lever 21 is operated the platen will likewise be moved simultaneously therewith. A guide rod 25 secured to the lever 21 operates in a perforation in the platen 10 for maintaining the arm in proper relation with said platen. A lug 26 is secured to the inner end of the lever 21 for a purpose which will be presently described.

100 Spaced journals 27 are mounted upon the

table 1 upon opposite sides of the slot 28 and are adapted to support a pivot pin 29. Pivotally mounted on the pin 29 is a pendulum 30 which passes through the slot 28 and is provided with adjustable weights 31 and 32 for varying the time of oscillation of said pendulum.

A stop lever 33 is hingedly mounted at 33^a to the rear of the pivot pin 29 on the table 1 and is provided with an arm 34 adapted to engage a bumper 35 on the upper end of the pendulum 30 and maintain the pendulum at an acute angle to the table 1 and thereby place the pendulum in a position to oscillate when the arm 34 has been removed from its engagement with the bumper 35.

A flexible member 36 has one end connected to the lug 26 on the lever 21 and its other end connected to a hook 37 mounted on the adjustable sleeve 38 which is slideable upon the stop lever 33. A spring 39 secured at one end to the stop lever 33 and at its other end to a post 40 is adapted to maintain the stop lever 33 in its most rearward position and for holding the pendulum 30 inclined at an angle to the table 1 and in the position shown in Figure 1.

A swingable lever 41 pivoted upon the pin 29 is adapted to be locked at its upper end to the upper end of the pendulum 30 by means of a U-shaped collar 42 which is secured to the pendulum.

Projecting at an angle to the lever 41 is a knife switch member 43 which is adapted to have timed engagements with a U-shaped contact 44 during the operation of the pendulum 30. The member 43 is provided with a conductor 45 which is carried downwardly along the lever 41 but insulated by the lever from the pin 29, and is adapted to engage a brush 46 formed in the block 47. The brush 46 is electrically connected with the binding post 48. The U-shaped contact 44 is electrically connected to the binding post 49.

As shown more particularly in Figure 3 the insulated conductor 50, which is connected with the binding post 48, is connected with the plug 51 which is adapted to be screwed into the ordinary socket connected with the house current. A switch 52 is located at any point upon the table 1 for breaking this circuit. The insulated conductor 53 connects the U-shaped contact member 49 with one end 54 of a rheostat 55 mounted in a casing 55^a. An arm 56 of the rheostat operated by a thumb piece 56^a electrically connects the wire 53 through the segments of the resistance 57 and a conductor 58 which leads to the resistance coil 59. The resistance coil 59 has a greater range than the smaller rheostat and therefore is more capable of reducing the intensity of the lamp 7.

An arm 60 is adapted to move over the contacts 61 and in the direction indicated by the arrow for decreasing the resistance to the lamp and therefore providing for a greater intensity of light, or when the arm 60 is moved in opposite direction indicated by the arrow, the resistance will be increased and therefore the intensity of light will be accordingly decreased. The arm 60 is shown in Figure 1 as movable over the contacts 61 which are secured to the side 60^a of the casing 6. The rheostat 59 is shown as mounted within a casing 59^a secured to the light bulb casing 6. The wire 62 runs from the arm 60 to the light bulb 7 and through the wires 63 back to the socket 51. The red light 8 is adapted to be in circuit with the house current when the switch 52 is closed whereby it is possible to have sufficient light for operating the printing machine without effecting the negative.

As shown more particularly in Figure 3 the greatest resistance will be had at the contact marked Z but such resistance is not sufficient to completely turn off the light. The resistance is sufficiently reduced at the second contact marked One to give, what I term a one light-unit of the lamp 7 for purposes of printing certain negatives. When the arm 60 is moved to the contact marked One and a quarter the resistance is sufficiently reduced to give one and one-quarter light units. The next contact gives one and a half light units. The fifth contact gives two units and so on as noted by the corresponding numbers opposite the succeeding contacts. When the last contact is reached, it is designated by the numeral 64, the full strength of the lamp 7 is upon the negative and the greatest intensity of the light is therefore had.

The smaller rheostat 55 is operated in conjunction with the rheostat 59 and is divided in tenths as shown. The resistance had by the small rheostat is equal to the resistance between any two of the contacts of the larger rheostat so that when the smaller rheostat is operated in conjunction with the larger rheostat the resistance will be added to the resistances of the larger rheostat and thereby vary the intensity of the lamp to a greater degree.

The operation of my device is as follows:

The negative 65 is placed in position on the transparent member 5 and the printing paper 66 is located upon the negative 65. The lever 21 is moved downwardly as shown in Figure 2 in dotted lines until the felt members 20 engage the paper 66. The hinged block 14 permits said block to be moved upon its hinge and raised to permit inspection of the paper on the negative in order to determine that it is correctly positioned on the transparent member 5. When the arm 21 is moved to the dotted line posi-

tion the flexible member 36 is made taut as shown in dotted lines.

In order to permit the pendulum 30 to operate the lever 21 is depressed against the 5 tension of the springs 23 and 24 and moved in close association with the platen 10. Since the flexible member 36 has been extended in taut relation by the lowering of the lever 21 and the platen 10, further movement of said lever will cause said flexible member to move the stop lever 33 forwardly and likewise the arm 35 away from the bumper 34 of the pendulum 30. This releases the pendulum and permits the same to 15 swing when the knife contact 43 will move into engagement with the U-shaped contact 44 thereby closing the circuit to lamp 7 and causing an instant flash in said lamp. The lever 21 may be released when the spring 39 20 will return the stop lever 33 to its normal position and prevent the pendulum 30 from further swinging movement. If it be desired to release the lever to obtain more than one flash, the pendulum 30 may be permitted 25 to swing and make any number of contacts desired between the members 43 and 44.

If it is desired at any time to change the time of oscillation of the pendulum 30, the weights 31 and 32 may be adjusted accordingly.

If at any time it be desired to disconnect the pendulum 30 from the lever 41 the set screws 67 and 68 may be released from their engagement with the lever 41 whereby the 35 yoke 42 may be removed and thus disconnect the lever 41 from the pendulum 30.

The set screws 67 and 68 may be so adjusted as to move the lever 41 slightly out of alignment with the pendulum 30 and 40 change the time of contact between the members 43 and 44, or where the members 43 and 44 do not properly contact at the time desired the set screws 67 and 68 may be adjusted to effect the proper positioning of 45 the lever 41 and thereby correct variations in the time of such contacts.

A spring 70 connected at one end to the lug 26 and at its other end to the hook 71 on the table 1 returns the lever 21 and platen 50 10 to their normal inoperative position and out of engagement with the inclined portion 2 of the table.

It must be borne in mind that the values of the light intensities assigned to the various contact points shown in Figure 3 are 55 purely arbitrary and are for purposes of illustration only. These values may be varied according to determinations acquired from experiments and such variations may be 60 made without in any way affecting the scope of the invention.

The printer is shown as having a pair of co-operating coils tapped at regular intervals in order to vary the intensities of the 65 light as desired and where such close adjust-

ment is not required, the small rheostat may be disregarded and the larger coil may be tapped at such intervals as to provide any form of scale of intensities.

The scale of successive light intensity 70 values may be made to approximate a geometrical progression which permits the use of a sliding or shifting scale to compensate for variations in the speeds of different makes of papers. 75

Not only does the speed of the different makes of papers affect the selection of the proper resistance but the density of the negatives must be taken into consideration, since the amount of light transmitted by a 80 negative is an important factor in the production of good prints. Therefore, the adjustment of the resistance element must be correlated in accordance with the transparency of the negative and speed of the paper. 85

What I claim is:

1. In a printing machine for printing of photographic prints, an electric circuit, an illuminating device in said circuit, means for supporting a negative and photographic 90 printing paper within effective light exposed relation with the illuminating device, a resistance in said circuit for varying the intensity of the light in accordance with the density of the negative, a movable platen 95 for maintaining the negative and paper in position at the time of exposure, means automatically set in motion upon the operation of the platen for closing and opening the circuit and timing the exposure of the photographic paper in accordance with the speed 100 of the paper, a lever for operating the platen, a resilient means for flexibly connecting the lever to the platen whereby said lever is capable of movement beyond the limits of movement of the platen, and means connecting the timing means with the lever whereby said timing means is set in operation when the lever is moved beyond the limit of movement of the platen. 110

2. In a printing machine for printing of photographic prints, an electric circuit, an illuminating device in said circuit, means for supporting a negative and photographic 115 printing paper within effective light exposed relation with the illuminating device, a resistance in said circuit for varying the intensity of the light in accordance with the density of the negative, a movable platen 120 for maintaining the negative and paper in position at the time of exposure, means automatically set in motion upon the operation of the platen for closing and opening the circuit and timing the exposure of the photographic paper in accordance with the speed 125 of the paper, said platen including a pivoted leaf adapted to be moved independently of the platen and out of engagement with the photographic paper, a lever for operating the platen, and resilient means connecting 130

the leaf and the platen to said lever whereby said lever is capable of movement beyond the limits of movement of the platen for releasing the timing means at this point in 5 the operation of said lever.

3. In a printing machine for printing of photographic prints, an electric circuit, an illuminating device in said circuit, means for supporting a negative and photographic 10 printing paper within effective light exposed relation with the illuminating device, a resistance in said circuit for varying the intensity of the light in accordance with the density of the negative, a platen for maintaining the photographic negative and paper 15 in position at the time of exposure, a lever for operating said platen and capable of movement beyond the limits of movement

of the platen, a pendulum adapted to be oscillated for closing and opening the circuit, means for locking the pendulum in an angular position relative to the vertical, means connected with the lever for releasing the locking means from its engagement with the pendulum and adapted to be operated upon the final movement of the lever which is beyond the limits of movement of the platen, said connecting means between the lever and the locking means comprising a flexible element adapted to be drawn taut 20 at the limit of movement of the platen, said flexible means being adapted to cause movement of the locking means by a subsequent movement of the lever. 25 30
